UNITED STATES PATENT OFFICE.

JAMES A. WILSON, OF CHICAGO HEIGHTS, ILLINOIS.

DISPLAY STAND.

Application filed November 7, 1921. Serial No. 513,230.

To all whom it may concern:

Be it known that I, JAMES A. WILSON, a citizen of the United States, and a resident of Chicago Heights, in the county of Cook 5 and State of Illinois, have invented certain new and useful Improvements in Display Stands; and I do hereby declare that the following is a full, clear, and exact description of the same, reference being had to 10 the accompanying drawings, and to the numerals of reference marked thereon, which form a part of this specification.

It is an object of this invention to provide a display stand with interchangeable tops 15 so that tops of various kinds may be secured upon the same pedestal.

It is a further object of this invention to provide such a stand with interchangeable tops in which the tops shall be securely held 20 in place without danger of accidental displacement and yet may be readily detached when it is desired to change them.

It is a further object of this invention to supply such interchangeable tops upon a 25 stand having a tilting head so that the tops may be placed at any desired angle.

Other and further important objects of my invention will appear from the following specification and the accompanying 30 drawings, in which I have illustrated and described my invention in a preferred form.

On the drawings:

Figure 1 is a side view of the stand with the style of top shown in Figure 7 attached 35 thereto.

Figure 2 is a side view of the head used in the stand.

Figure 3 is a top plan view of the stand with the style of top shown in Figure 6 attached 40 thereto.

Figure 4 is a plan of one style of top.

Figure 5 is a side view of another style of top secured to the stand.

Figure 6 is a plan of another style of top.

Figure 7 is a plan showing how a table 45 may be secured to the style of top shown in Figure 6.

Figure 8 is a section upon the line 8—8 of Figure 3.

Figure 9 is a section showing a modified 50 form.

Figure 10 is a section through one of the dowel pins of Figure 9.

As shown on the drawings:

55 The pedestal of the stand consists of a shaft 1 mounted upon a base 2 of any con-

ventional or desired form. The upper end of the shaft 1 is bifurcated as shown at 3 in Figures 5 and 8 and in the bifurcation is received the lower edge or flange of a tilting 60 head 5. The flange 6 has a hole 7 through it and through this hole and the sides of the bifurcation 3 goes a bolt 8 provided with a wing nut 11 whereby the head 5 may be secured at any desired angle. 65

The head 5 beside the downwardly extending flange 6 has two upwardly extending flanges 9. The flange 6 extends the whole length of the head but the flanges 9 stop short of the complete length of the head, 70 thus affording shoulders 10 and 10^a.

The form of top illustrated in Figure 6 is shown applied to the stand in Figure 3. It is used when the stand is for the purpose of displaying neckties or other articles 75 which can be hung over a single bar. It consists of a bar 12 ordinarily of rectangular cross section but not necessarily so. The central portion 13 of this bar is reduced to make a pair of shoulders 14 and 14^a on each 80 side of the bar at each end of the reduced portion 13. The distance between the shoulders 14 and 14^a is equal to the distance between the shoulders 10 and 10^a and the width of the reduced portion 13 is equal to 85 the distance between the flanges 9. Preferably also the thickness of the bar 12 at the part 13 is the same as the depth of the groove between the two flanges 9. It will be noted that the shoulders 10^a and 14^a are 90 inclined and interfit and effectively prevent the displacement of the top due to the weight of supported objects.

The bar 12 therefore may be seated in this groove with the sides of the reduced portion 95 13 in contact with the flanges 9, the shoulders 14 and 14^a in contact with the shoulders 10 and 10^a, the bottom of the reduced portion 13 in contact with the bottom of the groove between the flanges 9, and the top of 100 the reduced portion flush with the top of the flanges 9. Thus a very firm seating is obtained and the bar may be securely held, but at the same time it can readily be removed by shifting it slightly upward and 105 lifting it straight out from the groove. The extensions 30 of the head 5 beyond the shoulders 10 and 10^a afford surfaces which come against the under side of the bar 12 and if the bar should stick a tool may be 110 introduced between one of these surfaces and the bar to pry the bar out of the groove.

If the bar should become marred by this tool the marks will be on the under side of the bar where they will not show.

In the modification illustrated in Fig. 7
5 the bar 12 is secured to the under side of a
table 15. Although Figure 7 shows a square
table, it is obvious that a round, oval or
other desired shape of table may be secured
10 to the bar 12 and applied to the pedestal in
the same way as the illustrated table.

Another form of top, illustrated in Figure
5, is made by joining the end of a bar 12 by
a mortise and tenon joint as illustrated at
16 to bars 17 in a plane at right angles to
15 the bar 12 but the bars 17 stand at an angle
to the surfaces of the bar 12 so that when
the head 5 is placed horizontal these bars
17 will occupy two parallel vertical planes
but will be themselves oblique sloping
20 steeply upward and to the left as seen in
Figure 5. The bars 17 are provided with
notches 18 in which cross rods or cross bars
of any desired pattern may be suspended.
The rack thus formed will serve for suspending
25 hosiery or neckties or similar articles.

The form of top illustrated in Figure 4
has a cross bar 20 whose cross section is the
shape and size of the cross section of the
reduced part 13 of the bar 12. The length
30 of bar 20 is however slightly greater than
the length of the reduced portion 13. It is
thus adapted to fit in the groove between the
flanges 9. At each end of the bar 20 are
secured pieces 21 and 22 at right angles to
35 the bar 20. The distance between the pieces
21 and 22 is equal to the length of the re-
duced portion 13. These pieces afford a
bearing across the bar 20 which is analogous
40 to the shoulders 14 of the bar 12 in Figure 6
and when the bar 20 is placed in the groove,
the ends of the flanges 9 which afford the
shoulders 10 will abut against the pieces 21
45 and 22 and secure the same firm hold that
has already been described. By tilting the
head 5 the piece 22 may be made to be higher
than the piece 21 if desired. Preferably a
flange 23 is provided upon the piece 22, so
50 that it is higher than 21. This style of top
may serve to support a pair of shoes by
hooking the heels of the shoes over this
flange and letting the toes thereof rest upon
the piece 21.

The form of head illustrated in Figures 9
and 10 does not have the groove afforded by
55 the two flanges 9. It is however provided
with the downwardly extending flange 6 and
the hole 7 already described. The main

body 25 of this head from which the flange
6 descends is provided with two dowel pins
26. A top of any desired form 27 is pro-
60 vided with two holes at the same distance
apart as the two dowel pins 26. The top
therefore may be fitted onto the head by
slipping the dowel pins into these holes.

I am aware that many other styles of tops
65 besides those which I have illustrated may
be secured to the head in the way which I
have illustrated. I am also aware that
many details of construction may be varied
through a wide range without departing
70 from my invention, and I therefore do not
purpose limiting the patent granted other-
wise than necessitated by the prior art.

I claim as my invention:

1. In a display stand, a pedestal, a head
secured to said pedestal, upstanding parts
upon said head, a top provided with bearing
surfaces at an angle to one another, one of
said surfaces bearing against the body of
80 said head, the other of said surfaces bearing
against the upstanding parts.

2. In a display device, a pedestal, a head,
the head having a downwardly extending
flange and two upwardly extending flanges,
means pivoting the downwardly extending
85 flange to the top of the pedestal, said up-
wardly extending flanges affording a groove
between them, and a top having a portion
adapted to fit in said groove whereby said
top may be detachably secured to the head. 90

3. In a display device, a head, a pair of
parallel upstanding flanges thereon whereby
a groove is provided bounded by said flanges,
a shoulder at each end of each of said flanges,
a top having a portion of the width and 95
depth of said groove and having shoulders
at each end of each side of said portion,
whereby the shoulders upon the top are
adapted to contact with the shoulders upon
the flanges when the said portion of the top 100
is inserted in said groove.

4. In a display device, a base, a pedestal
rising from said base, a head pivotally se-
cured to said pedestal, a top comprising a
merchandise holder, a top support secured
105 to said top and detachably secured by join-
ery to said head.

In testimony whereof I have hereunto sub-
scribed my name in the presence of two sub-
scribing witnesses.

JAMES A. WILSON.
